RAIL DRILLING MACHINE

Henry H. Talboys, Milwaukee, Wis., assignor to
Nordberg Manufacturing Company, Milwaukee,
Wis., a corporation of Wisconsin

Application August 23, 1930, Serial No. 477,283

4 Claims. (Cl. 77—8)

My invention relates to an improvement in drills and has for one purpose the provision of a drill and drill structure applicable to drilling rails of railroad tracks. Another object is the provision, in such a structure, of means for readily and easily adjusting the height of the drill. Another object is the provision of adjustable abutment means, removably mounted in relation to the drill supporting structure, for engaging 5 the side of the rail opposite to the drill. Another object is the provision of a light and easily movable drill structure which may, for example, be manually transported along a rail. Other objects will appear from time to time in the course 10 of the specification and claims.

I illustrate my invention more or less diagrammatically in the accompanying drawings, where- 15 in—

Figure 1 is a side elevation illustrating the 20 structure in transporting position;

Figure 2 is a side elevation illustrating the 25 structure in operating position;

Figure 3 is a plan view;

Figure 4 is a section on the line 4—4 of Fig- 30 ure 2;

Figure 5 is a section on the line 5—5 of Fig- 35 ure 1;

Figure 6 is a partial side elevation; and

Figure 7 is a section illustrating the rail engag- 40 ing abutment and its connection with the drill structure.

Like parts are indicated by like symbols throughout the specification and drawings.

Referring to the drawings, A generally indicates the roadbed of a railroad track, upon which 45 are mounted ties A¹ carrying rails A².

B generally indicates the main frame which includes angle irons B¹ forming sides to a longitudinally extending end. The angles B¹ are 50 connected at one end by the transverse angle B² and at the other by a cross piece or plate B³. At each end of the frame, secured respectively to the angle B² and the plate B³ are the upwardly extending angles B⁴ B⁵ to which may be welded 55 or otherwise secured transverse plates or strips B⁶, through the outwardly extending ends of which are inserted the supporting or carrying shafts B⁷. They may be held in position for example from Figures 1 and 3 that the ends of the shafts B⁷ project sufficiently outwardly at each end of the drill structure to permit an operator to stand between the shafts and engage each shaft with one hand in the manner of the carrier 60 of a sedan chair.

Mounted upon the above described frame in any suitable fashion is a motor structure indicated as C, the details of which form no part of the present invention and therefore are not herein described in detail. C¹ indicates a motor shaft and C² generally indicates a clutch structure controlled for example by the manual lever C³.

D generally indicates the transmission structure which may for example include the transmission housing D¹ in which may be positioned any suitable gear reduction. D² indicates a shaft extending from the clutch structure C² which is in driving relation with the gear reduction. D³ indicates a shaft from the gear reduction 65 which carries the sprockets D⁴ about which pass the sprocket chains D⁵ to the lower sprockets D⁶ which drive the drill head or shaft D⁷, in which may be removably positioned any suitable 70 drill or bit member D⁸.

E generally indicates any suitable feed mechanism for feeding the shaft and head D⁷ toward the work, the work being herein shown for example as the rail A². This feed mechanism may include the feed screw or worm E¹ driven by a 75 concentrically threaded gear E² in mesh with the pinion E³ upon the shaft E⁴ which in turn is driven through the gear E⁵ which in turn is driven by the pawl E⁶ on the rock lever E⁷ which is oscillated by the arm E⁸ and the link E⁹ 80 rotatably mounted upon the arm E¹⁰ on the shaft D³. It will be understood that the work may be forwardly fed manually, when the machine is not in operation, by employment of the manual crank E¹¹ upon the shaft E⁴. This manual feed may be 85 employed to move the drill forwardly into contact with the rail and may also be employed to withdraw it from contact with the rail after the drilling operation is completed. During the drilling operation proper the feed is in response to rotation of the crank E¹⁰. The feed mechanism and the shaft D⁷ are mounted in a channel member E¹² supported by angles E¹³ from the main frame members B¹. Pins E¹⁴ project outwardly from the sides in the structure so formed, being for example welded thereto.

G generally indicates an abutment member for engaging the opposite side of the rail from that which is being drilled. It includes for example the upwardly inclined fork members G¹, the transverse connecting structure G² with the adjusting set screw or bolt G³ and the downwardly extending arm G⁴. The arm G⁴ forks at its lower end as at G⁵, the tines of the fork G⁵ inclining 100 inwardly as well as downwardly and terminating 110

in rail engaging studs or enlargements G^6 . G^7 G^7 indicate securing ends on the forks G^1 , which are notched on their lower edges as at G^8 , to seat upon the pins E^{14} . By employing a plurality of 5 notches it will be seen that a longitudinal adjustment of the drill structure in relation to the fork or abutment member is permitted. By the employment of open notches a ready removability of the abutment from the drill structure is also 10 provided. The screw G^3 serves to adjust the height of the fork in relation to the rail and permits lining up of the members G^6 in line with the axis of the drill. The fork in the members G^5 permits the drill to pass entirely through the 15 rail without interruption from the abutment.

H indicates a base structure which includes the plate H^1 and the angles H^2 H^2 extending from one end thereof, the members H^2 being connected by the transverse brace or angle H^3 . H^4 H^4 are brackets 20 upwardly extending from the members H^2 , having slots through which may pass the pivot pin H^5 . This pivot pin passes also through brackets H^6 , the upper ends of which are secured to the side frame members B^1 . It will thus be 25 seen that the drill supporting structure above described is pivotally mounted upon the base members H^1 H^2 . In order to effect an adjustment of the drill supporting structure in relation to the base I employ the following mechanism. Mounted at the outer end of the member H is a 30 cup H^7 adapted to receive the head H^8 of the socket H^9 , the head being held against escape from the cup for example by the pins H^{10} . Pinned to the socket H^9 is the screwthreaded shaft H^{11} which passes through the screwthreaded member or nut H^{12} . This screwthreaded member H^{12} may be mounted upon or welded to one of the transverse channel members H^{13} which serve as supports 35 from the gear reduction housing D^1 previously described. H^{14} is an aligning bearing for the upper portion of the shaft H^{11} and H^{15} is a manual handle pivoted as at H^{16} , to the upper end of the shaft H^{11} . It will be understood that rotation 40 of the shaft H^{11} will cause the main frame and the drill structure mounted thereon to be tilted upwardly or downwardly in relation to the base members H^1 , H^2 . Inasmuch as the drill structure is removed from the pivot pin H^5 this 45 tilting of the drill supporting structure causes an upward or downward adjustment of the drill in relation to the base member H . In order to permit the drill to reach the lowest possible adjustment the channel member E^{12} is cut away as at E^{20} , as shown for example in Figure 4, to permit 50 the passage therethrough of the member H^1 when the device is at its lowest adjustment.

Pivoted for rotation about the pin H^5 are the 55 arms J connected by the transverse member J^1 the whole forming an H -shaped structure. At one end of the H is a pivot pin J^2 , mounted upon which is the track engaging roller J^3 , flanged at each side as at J^4 . The opposite ends of the arms J are apertured as at J^5 to receive the passage therethrough of the locking pin J^6 having the offset end or handle J^7 . One end may be split as at J^8 to give a frictional or gripping engagement with the apertures through which it passes. Each of the brackets H^6 is apertured as at J^9 to permit 60 the passage of the pin J^6 . The side frame members B^1 are similarly apertured as at J^{10} . It will be understood that by employment of the pin J^6 , passing through the said apertures, the arms J , and thus the wheel J^3 , may be secured selectively 65 to the operative position in which they are shown 70 75

in dotted line in Figure 1, or in the inoperative position in which they are shown in full line in the same figure.

It will be realized that whereas I have shown and described a practical and operative device, nevertheless many changes might be made in the size, shape, number and disposition of parts without departing from the spirit of my invention. I therefore wish my description and drawings to be taken as in a broad sense illustrative and diagrammatic rather than as limiting me to my specific showing. In particular it will be understood that although I have shown my drill and abutment structure as adapted for and applied to use with railroad rails, I do not wish to be so limited, since the same structure may be employed for other purposes and in other connections. 80 85 90

The use and operation of my invention are as follows: 95

I have provided a drilling structure which is particularly adapted to use upon railroad tracks, rails and the like, although I do not wish to limit it to such use. It includes the base structure H^1 H^2 which may rest for example upon the roadbed or upon the ties and which serves as a support or base for the whole structure when in use. The main frame or drill supporting structure, including the side frame members B^1 , is pivoted as a unit for rotation about the pivot pin H^5 . The drill proper is at the end of the main frame remote from the said pivot and therefore rotation of the main frame imparts a substantially vertical movement to the drill, upwardly or downwardly in relation to the track. 100 105 110 115 120 125 130 135 140 145 This adjustment may be obtained by rotation of the screwthreaded shaft H^{11} which seats in the cup H^7 on the member H^1 . Referring for example to the position of the parts in Figure 4, rotation of the shaft H^{11} will lift the drill shaft and head D^7 to any desired height in relation to the object being drilled, in this instance a rail. In order to permit the employment of a light drill and drill supporting structure, of insufficient weight to hold itself in position, and not fastened down, I employ the abutment structure generally indicated as G . The forks G^1 are hooked over the pins E^{14} , the slots G^8 providing a longitudinal adjustment, depending upon which slots engage the pins E^{14} . The ready removability of the abutment member G is an advantage, since the end may be hooked into restricted spaces, such as the space between the two rails shown in Figure 7, which it will be unable to penetrate were it fixed in relation to the heavy and relatively immobile drill structure. For example the hook may be slid in between two rails or tilted into position to penetrate between two rails. When positioned in the restricted space it may then be hooked to the pins E^{14} . Preferably the abutment members G^6 of the fork arms G^5 are horizontally aligned with the axis of rotation of the drill. This alignment may be obtained by rotation of the screw G^3 . Thus I may compensate for rails of different height, and for different adjustments in height of the drill. The drill member may pass entirely through the web of the rail, since it will pass between the fork tines G^5 .

In transporting the device as a whole from place to place, two operators may carry it like an old fashioned sedan chair, each operator grasping adjacent ends of the supporting bars B^6 . The wheel J^3 may, if desired, be positioned in the dotted line position of Figure 1, to engage 150

one of the rails and to support a part or substantially all of the weight. In such a case one man may wheel the device like a wheelbarrow along the rail, or two men, one at each end, may guide

5 the device, the weight being supported by the wheel. When the device is in operative position the wheel is swung into the full line position in which it is shown in Figure 1.

I claim:

10 1. In a track drill, a base presenting a flat supporting surface normally engaging and resting upon the road bed, and extending substantially parallel with the rail, a frame pivoted to said base, a drill, mechanism for actuating said

15 drill and driving means for the actuating mechanism, all carried by said frame over the base and in longitudinal alignment therewith, whereby all of the weight is transmitted to the base, and means for actuating the pivoted frame to 20 raise or lower the drill, said base and surface being substantially coextensive with the length of the frame.

25 2. In a track drill, a drill supporting structure, a drill therein, an abutment member having one portion engaging the rail opposite the drill and in horizontal alignment therewith and having another portion removably attached to the drill supporting structure, said attaching connection including projections on the drill support, said 30 abutment having a shank provided with a plurality of notches in pairs on the lower edge thereof, any pair of which is engageable with the

projections whereby the abutment is quickly removable from the drill supporting structure, and is adjustable both longitudinally and angularly.

3. In a track drill, a base presenting a flat supporting surface normally engaging and resting upon the road bed and extending substantially parallel with the rail, a drill and driving mechanism therefor mounted on the base, said base lying along substantially the medial longitudinal plane of the machine, said base and surface being substantially coextensive with the length of the machine whereby all the weight is transmitted through the base to the road bed. 80

4. In a track drill, a drill supporting structure, a drill thereon, an abutment member having one portion engaging the web of the rail on the side opposite from that of the drill and in horizontal alignment therewith, and having another portion removably attached to the drill supporting structure, said attaching connection including projections on the drill support, said abutment having a shank provided with a plurality of notches in pairs on the lower edge thereof, any pair of which is engageable with the projections whereby the abutment is quickly removable from the drill supporting structure and is adjustable both longitudinally and angularly, and means engaging the rail and operable to move the abutment angularly about its point of attachment. 90 95 100 105
